UNITED STATES PATENT OFFICE

ERNEST G. OFELDT, OF NYACK, NEW YORK.

SPRING-TIRE.

No. 829,996.

Specification of Letters Patent.

Patented Sept. 4, 1906.

Application filed December 9, 1905. Serial No. 291,119.

To all whom it may concern:

Be it known that I, ERNEST G. OFELDT, a resident of Nyack-on-the-Hudson, in the county of Rockland and State of New York, have invented certain new and useful Improvements in Spring-Tires; and I do hereby declare the following to be a full, clear, and exact description of the invention, such as will enable others skilled in the art to which it appertains to make and use the same.

My invention relates to improvements in metal spring-tires, the object of the invention being to provide an improved wheel-tire in which steel or other metal springs are interposed between an inner and an outer ring or casing, said springs secured to the inner ring and bowed under tension to maintain a uniform pressure on the outer ring or casing throughout its circumference; and the invention

consists in certain novel features of construction and combinations and arrangements of parts, as will be more fully herein-after described, and pointed out in the claim.

In the accompanying drawings, Figure 1 is a view, partly in longitudinal section, illustrating my improvements. Fig. 2 is a view in cross section, and Fig. 3 is a view of one of the springs removed.

1 represents a channel-iron ring constituting a part of the tire, and 2 is an outer ring of greater diameter than ring 1 and connected therewith at its edges by flexible strips 3, of any suitable material, secured to both rings, or this outer ring 2 and side strips 3 may constitute a single flexible inclosing casing or outer cover, of rubber, leather, or other material.

4 represents my improved springs, each of which has a base portion 5, to be secured by rivets 6 or otherwise to the channel-iron ring 1 between the side flanges thereof, and while the main portion of the spring is straight or slightly curved and diminishes in thickness from its inner end outward when in position in the tire it is bowed back and its end presses upon the next adjacent spring to always exert an outward pressure on outer ring 2 and maintain a distended tire at all times

throughout the circumference thereof and at the same time most effectually cushioning the same.

From the construction above described it will be seen that each spring presses at a point rearward of its free extremity against the outer ring, and at its free end each spring presses against the adjacent spring rearwardly of the bearing of the latter against the outer ring.

It will also be seen that a tire is produced in which a uniform cushion is provided throughout the entire circumference, as the springs coöperate with each other to form a cushion and sustain the weight. The strength and rigidity of the cushion will depend upon the number of springs employed and their strength.

Slight changes might be made in the general form and arrangement of the parts described without departing from my invention, and hence I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

A tire comprising an inner ring, an outer ring, annular flexible strips fixed at their respective edges to said rings, and a series of springs inclosed by said rings and strips, each of said springs diminishing in thickness from one end to the other and secured at their thicker ends to the inner ring, each spring pressing at a point rearward of its free end against the inner face of the outer ring and pressing at its free extremity against the adjacent spring at a point rearward of the bearing of the latter against the outer ring.

In testimony whereof I have signed this specification in the presence of two subscribing witnesses.

ERNEST G. OFELDT.
